[57] **CLAIM**

The ornamental design for a tire, substantially as shown and described.

DESCRIPTION

FIGS. 1, 2, 3 and 4 are perspective views of a tire showing four embodiments of my new design, it being understood that the tread pattern is repeated throughout the circumferences of the tire, as shown schematically by solid lines, the opposite side being substantially the same as that shown.

FIG. 1

FIG. 2

FIG. 3

FIG. 4
